UNITED STATES PATENT OFFICE.

CHARLES H. HOWE, OF PLAINFIELD, NEW JERSEY, ASSIGNOR TO ALPHA GAMMA DELTA
FRATERNITY, OF SYRACUSE, NEW YORK, A CORPORATION OF NEW YORK.

DESIGN FOR A RECOGNITION PIN OR BADGE.

51,163.

Specification for Design.

Patented Aug. 14, 1917.

Application filed January 11, 1916. Serial No. 71,592. Term of patent 3½ years.

To all whom it may concern:

Be it known that I, CHARLES H. HOWE, a citizen of the United States, residing at Plainfield, in the county of Union and State of New Jersey, have invented a new, original, and ornamental Design for Recognition Pins or Badges, of which the following is a specification, reference being had to the accompanying drawing, forming a part hereof.

The drawing is a face view of the pin or badge illustrating my new design.

This design for recognition pin or badge comprises a quadrilateral, oblong body or background on which are three embossed

circles which are disconnected and spaced apart from each other, the three circles extending over or filling nearly the entire area of the background.

I claim:

The ornamental design for recognition pin or badge, substantially as shown and described.

In testimony whereof, I have hereunto signed my name, at New York, in the county of New York, and State of New York, this 27 day of October, 1915.

CHAS. H. HOWE.
